UNITED STATES PATENT OFFICE.

RASMUS T. BERTELSEN, OF CHICAGO, ILLINOIS.

GRILLE.

SPECIFICATION forming part of Letters Patent No. 517,207, dated March 27, 1894.

Application filed January 4, 1894. Serial No. 496,643. (No model.)

To all whom it may concern:

Be it known that I, RASMUS T. BERTELSEN, of Chicago, in the county of Cook and State of Illinois, have invented certain new and 5 useful Improvements in Grilles; and I do hereby declare that the following is a full, clear, and exact description thereof, reference being had to the accompanying drawings, and to the letters of reference marked thereon, 10 which form a part of this specification.

This invention relates to an improvement in grilles or ornamental gratings such as are commonly applied to upper parts of door and window openings or other similar places 15 in houses.

The invention consists in the matters hereinafter described and pointed out in the appended claims.

Grilles of that kind adapted to extend across 20 the entire width of the doorway or opening have commonly heretofore been made in one piece constructed of proper length to accurately fit the opening, the grilles being fitted at their margins within the openings so as to 25 abut at their edges against the side and top surfaces of the same. Grilles thus made have not commonly been manufactured and sold as an article of commerce for the reason that the width of the openings to which they are 30 applied are seldom the same or they vary to an extent so great as to prevent the grilles being made in standard sizes and cut off or trimmed to fit the openings. As a consequence such grilles have usually been made 35 to measurement so that each will fit the opening for which it is designed, thereby requiring in effect a new design or the adaptation of an old design to each grille with a corresponding increase of cost by reason of the 40 special labor required in making each article.

The object of this invention is to provide a grille which will be adjustable to openings of various widths within certain limits, so that by carrying in stock a number of sizes a 45 dealer may supply his customers with grilles which will practically fit all doorways or openings.

A grille embodying my invention consists of two, three or more parts which are separately attached in place within the opening 50 so as to give the appearance of a single grille, said parts being made of any ornamental

shape desired and being connected where they join by horizontally arranged filling pieces or sections which may be shortened or lengthened to fill the spaces between the main sections of the grille and thus give an appearance of continuity to the same. The filling pieces or sections of variable length are herein shown as formed by means of rods or dowel-pins inserted at their ends within the adjacent edges of the grille sections and provided with one or more buttons or spools of ornamental form placed or strung thereon so as to fill or approximately fill the spaces between the grille sections, the number of these buttons or spools being varied to correspond with the distance apart at which the adjacent margins of the sections stand when the grille is in place in the doorway. The rods or dowel-pins are constructed to slide in guide apertures in one or both of the grille sections so that in placing the grille sections in the opening said rods and dowel-pins will be self-adjusting and no labor or manipulation will be required in putting the parts of the grille together except to place or string on the rods or dowel-pins a number of buttons or spools sufficient to fill the spaces between the grille sections.

The invention may be more readily understood by reference to the accompanying drawings, in which—

Figure 1 is a view in side elevation of a grille embodying my invention. Fig. 2 is an enlarged detail view, with parts in section, of an adjustable section adapted to be placed between two of the grille sections. Fig. 3 is a view showing two of the grille sections separated from each other to a greater extent than illustrated in Fig. 1 and showing additional connecting sections which may be employed under these circumstances. Fig. 4 is a detail sectional view of a rod or dowel-pin, showing buttons or spools of different forms.

The grille illustrated in the accompanying drawings consists of three pieces or main sections, to wit, two end pieces A A which fit within the corners of the doorway or other opening, and an intermediate section B which is placed between the sections A A when the grille is placed in position within the opening. The grille sections A A are provided with upper and horizontal marginal pieces or strips

a a' which come in contact with the vertical and top walls of the opening, and the intermediate section B is provided at its upper edge with a similar continuous marginal strip 5 b. The continuous marginal pieces or strips *a a' b* are commonly present on all grilles of this character, the same constituting in effect a framework to sustain the inner or ornamental parts of the grille or grating and affording a means for attaching the same within the opening which the grille is intended to fill. When the grille is made in sections, as described, the horizontal marginal pieces or strips *a a' b* of the end and intermediate sections are obviously discontinuous and when the sections are separated to a greater or less extent so that they may fit the doorway in which they are placed, spaces of greater or less width will be left between the adjacent 20 ends of said strips. To give an appearance of continuity to the strips, however, I provide horizontal rods or dowel-pins C C which are inserted at their ends in horizontal guide apertures placed opposite each other, and I 25 place on said rods or dowel-pins one or more balls, buttons or ornamental spools D D, the same being made relatively narrow so that they may either solidly fill that part of the dowel-pin which is exposed between the grille 30 sections or may be placed at equidistant or other points thereon so as to produce an ornamental effect or give the appearance of a turned spindle interposed between the parts and intended for ornament. Commonly buttons 35 will be used which are relatively narrow so that they will approximately fill the space between the grille sections and thus afford a connecting section of sufficient size to give the effect of continuity to the marginal strip 40 of the grille.

At one or more points along the adjacent edges of the grille sections I place other similar connecting sections; as for instance, in Fig. 1 a similar dowel-pin C is placed near the 45 lower margin of the grille and is provided with similar balls or buttons D D.

The number of connecting sections such as is described which will be employed on the grille will depend on the particular character 50 of the ornamentation, as for instance in the grille shown in Fig. 1 the intermediate ornamental scrolls between the two connecting sections at the top and bottom of the grille are of such character that they may be brought 55 close together, as shown in said figure, or separated to some extent without removing or affecting the ornamental character or appearance of the grille. If, however, the sections are more widely separated other connecting 60 sections may be inserted, even though the same are not necessary or desirable where the separation of the main sections is not so great; as for instance in Fig. 3 are shown the adjacent ends of grille sections, like those shown 65 in Fig. 1, more widely separated and having a greater number of buttons or balls on the upper and lower dowel-pins C C. In this in-

stance also the opposite intermediate loops *a³* *b³* of the scroll ornaments are connected by additional dowel-pins C C similarly provided 7c with balls or buttons D D.

The horizontal rods or dowel-pins described may be constructed in any suitable manner and may be secured in one of the grille sections or made to slide freely in both, as desired. As shown in Fig. 2 the dowel-pin C is made of wood and is provided with an integral ball or button c resembling in appearance the loose balls or buttons D D which are placed thereon. In this instance the dowel-pin is driven into one of the sections until the ball c thereof comes in contact with the edge of the section while the opposite end of the dowel-pin is left free to slide within the guide aperture of the opposite or adjacent 85 section.

As shown in Fig. 4 the rod or dowel-pin C consists of a metal rod or wire inserted in opposite guide apertures in the grille sections. In this instance the rod C is provided with a 90 central ornamental spool d with two plain spools or sleeves *d' d'* at opposite sides thereof and two flat buttons *d² d²* between the said spools and the adjacent margins of the grille sections. Said Fig. 4 illustrates clearly the 95 variety of form which the balls or buttons may be given in order to secure the result desired, to wit, the appearance of continuity or integrality while affording longitudinal adjustment of the entire grille within reasonable 100 limits.

It is obvious from the above that the adjustable connecting sections referred to by which the effect of continuity is given to the main sections consist of a plurality of relatively narrow pieces or elements, as for instance, the balls or spools D D, of which a greater or less number may be used and which are properly supported between the grille sections, as for instance by the dowel-pin or rod 110 C, and I do not, therefore desire to be limited to the special form of the connecting sections illustrated.

Where the grille-sections are so slightly separated that one ball or button only is 115 needed to fill the space between them, the same may consist of an apertured ball placed centrally on the dowel pin between the sections, or it may be a ball or projection made integral with the dowel pin, such as is seen 120 in Fig. 2. When balls are used which are placed on the dowel pin or rod with spaces between them, the said dowel pin will obviously be exposed between the buttons and will thus form a visible part of the connecting section, but when the space is such that the number of buttons or balls which may be placed between the sections will be such as to practically fill the said space, then the dowel pin or rod will be practically invisible and 125 its main function then will be to form a support for the balls or buttons.

The particular construction herein illustrated, wherein a round rod or dowel-pin is

inserted in opposite holes in the grille sections, and turned buttons or spools provided with central apertures are placed on said rod or dowel-pin, is, however, of special value and 5 utility by reason of its simplicity, cheapness and effectiveness for the purpose intended, and a construction of this kind is therefore herein specifically claimed as part of my invention.

10 I claim as my invention—

1. A grille consisting of a plurality of main sections separated from each other and adapted to be placed within a doorway or other opening, and connecting sections comprising one or more small pieces or elements, such as the spools or buttons D D, and means for supporting said small parts or elements in 15

place between the adjacent grille sections so as to give the appearance of continuity to the same, substantially as described.

20

2. A grille comprising two or more grille sections, and connecting sections each consisting of a dowel pin or rod inserted in opposite apertures in the sections, and one or more apertured buttons or spools placed upon the 25 said dowel-pin or rod, substantially as described.

In testimony that I claim the foregoing as my invention I affix my signature in presence of two witnesses.

RASMUS T. BERTELSEN.
